UNITED STATES PATENT OFFICE.

LYDIA E. JOSLIN, OF LOS ANGELES, CALIFORNIA.

ERASER CLEANER.

Application filed June 9, 1926. Serial No. 114,772.

The present invention relates to erasers, especially those used for erasing typewritten matter, and the object of the invention is the provision of simple, novel and efficient 5 means for keeping the edge of a disk-shaped eraser clean.

With the foregoing and other objects in view, which will be apparent as the description proceeds, the invention resides in the 10 construction and arrangement of parts, as hereinafter described and claimed, it being understood that changes can be made within the scope of what is claimed, without departing from the spirit of the invention.

15 The invention is illustrated in the accompanying drawing, wherein—

Figure 1 is a side elevation of a typewriter eraser with the cleaning device applied.

20 Fig. 2 is an edge view thereof.

In the drawing there is shown a typewriter eraser of well known construction, comprising a disk-shaped eraser proper, indicated at 7, a brush 8 secured within a 25 socket 9 projecting radially from the eraser 7, and said socket 9 having ears or side plates 10 overlapping the opposite sides of the eraser 7 and pivotally connected to the eraser by means of an eyelet or rivet 11, 30 whereby the brush and eraser may be rotated relatively to one another about the pivot 11 to present the different portions of the edge of the eraser for use.

In carrying out the present invention an 35 arm 12, preferably of sheet metal, is disposed tangentially of the edge of the eraser 7, and has a bifurcated terminal with ears 13 overlapping the opposite sides of the brush socket or member 9 and pivoted there- 40 to, by a rivet 14, whereby the arm 12 may swing toward and away from the edge of the eraser. The axis of the rivet or pivot element 14 is parallel to the axis of the pivot 11. A leaf spring 15 bears against the outer 45 side of the arm 12 for swinging said arm yieldingly against the edge of the eraser under pressure, and said spring 15 is secured to the socket 9 in any suitable manner, such as by means of a band 16 embrac- 50 ing said socket.

The arm 12 has bent back edge portions 17 at opposite sides of the eraser for re-

ceiving and holding on the inner side of the arm 12 a small sheet or piece of abrasive material, as at 18, whereby said material 55 bears under the pressure of the spring 15 against the edge of the eraser or disk 7.

By rotating the disk or eraser 7 relatively to the brush 8, the edge of the eraser in contacting with the abrasive material or piece 18 will be cleaned, and said material or piece 18 may be replaced, if worn out before the eraser 7 is worn down.

Having thus described the invention, what is claimed as new is:—

1. In a device of the character described, the combination with a disk-shaped eraser, a pivot element engaging through the center thereof, and a radially extending member engaging said pivot element, of an abrasive holding member pivoted to the first-named member to swing about an axis parallel to the axis of said pivot element and adapted to be forced against the edge of the eraser.

2. In a device of the character described, the combination with a disk-shaped eraser, a pivot element engaging through the center thereof, and a radially extending member having ears overlapping the opposite sides of the eraser and engaging said pivot element, of a spring-pressed cleaning means having a bifurcated portion mounted on said member for the movement of said means against the edge of the eraser.

3. In a device of the character described, the combination with a disk-shaped eraser, a pivot element engaging through the center thereof, and a radially extending member engaging said pivot element, of a spring-pressed cleaning means pivotally connected to said member to swing about an axis parallel to the axis of said pivot element against the edge of the eraser.

4. In a device of the character described, the combination with a disk-shaped eraser, a pivot element engaging through the center thereof, and a radially extending member engaging said pivot element, of an arm pivoted to said member to swing about an axis parallel with the axis of said pivot element and having abrasive material thereon to contact with the edge of the eraser.

5. In a device of the character described,

the combination with a disk-shaped eraser, a pivot element engaging through the center thereof, and a radially extending member engaging said pivot element, of an arm pivoted to said member to swing about an axis parallel with the axis of said pivot element, said arm having bent back edge por-

tions to receive a piece of abrasive material so as to engage the edge of the eraser, and spring means for swinging said arm toward the eraser.

In testimony whereof I hereunto affix my signature.

LYDIA E. JOSLIN.
